STABILIZING DEVICE FOR AERIAL NAVIGATION MACHINES

Etienne Edmond Oehmichen, Valentigney, France
Application October 28, 1935, Serial No. 47,173
In France October 31, 1934

4 Claims. (CL. 244—4)

This invention relates to aircraft, and more particularly to devices for stabilizing aircraft.

Devices of the kind referred to comprise a closed volume such as an envelope filled with a gas, e. g. atmospheric air, the general center of gravity of the entire machine being determined by all masses forming part of the machine, including the gas contained in said envelope.

It is an object of the present invention to establish in machines of the type aforesaid distinct positions for the general center of gravity and for the center of static pressure, and to simultaneously provide for as close as possible or even identical positions for both the general center of gravity and the center of the aerodynamic pressures resulting in the propulsion of the aircraft.

This is to say that when the craft starts moving horizontally in any direction, the principle of this invention is realized by the resulting aerodynamic resistance being applied as near as possible to the general center of gravity of the craft and by the center of volume being simultaneously spaced as far as possible from and above the general center of gravity.

The reasons for this arrangement will be explained hereafter. They are based on a general theory, established by the inventor, of the equilibrium of a body heavier-than-air, which is sustained by mechanical means and may remain floating in the air in the absence of any horizontal velocity.

This theory, which will be explained below at least in its outlines, leads to the arrangements according to the invention, which have been completely supported by experience. The invention has been tested by means of reduced models wherein the said conditions have been realized.

In the drawings affixed to this specification and forming part thereof several embodiments of my invention are shown diagrammatically by way of example.

In the drawings—

Figs. 1, 2 and 3 are diagrammatical elevations of three models of helicopter devices adapted to demonstrate the invention.

Figs. 4, 5 and 6 are diagrams illustrating the theory underlying the invention.

Figs. 7, 9 and 11 are end elevations, and

Figs. 8, 10 and 12 are the corresponding side elevations of various stages of development of the invention.

Fig. 13 is an end elevation, and

Fig. 14 is a side elevation of one embodiment of the invention.

Fig. 15 is an end elevation of a modification of the embodiment shown in Figs. 13 and 14.

Fig. 16 is a side elevation, and

Fig. 17 is an end elevation of another embodiment of the invention.

Referring now to the drawings, and first to Figs. 1, 2 and 3, a rectangular frame 1, 2, 3, 4 supports two helicopter screws 5 and 6, placed on both the sides of the bar 2; 3 and rotatable in inverse directions under the action of a mechanical motor, which is mounted in a vertical cylinder 7.

Small ballonets 8 and 9, inflated with air, may be adjusted to the frame and displaced along the frame struts 1, 2 and 3, 4 respectively, with the aid of collars 10 and 11. They may occupy any desired position along the struts 1, 2 and 3, 4 as shown in dotted lines in Fig. 1. Resistance planes in the form of the so-called auxiliary planes 12 and 13 may be fixed on different points of the struts 1, 2 and 3, 4.

When the device is centered, i. e. when the air resistance to the lateral displacements is applied to the general centre of gravity 15 and when at the same time, the static pressure, the centre of which is indicated at 14 (Fig. 2), lies above the said general centre of gravity, the equilibrium is quite perfect, whatever may be the angle, under which the aircraft is left off. The latter may even be left to itself in overturned position; it will get upright again every time.

If the aircraft is not aerodynamically centered, the equilibrium is far from being correct and it is necessary to make use of a much more powerful static couple in order to bring the machine out of the bank.

Moreover, the completely closed chambers, such as the ballonets, may be replaced by cylindrical chambers 16 and 17 (Fig. 3) open at their bottoms and insuring only a partial solidarization between the air contained in the chamber and the aircraft itself. The equilibrium is nearly as good as in the case of a completely closed chamber.

In order to abridge the explanation of the theory, I will only:

(1) Explain the hypotheses, on which this theory is founded,

(2) Indicate the equations resulting from the application of the laws of theoretical mechanics according to these hypotheses,

(3) Set forth the results obtained by the integration of the said equations and the conclusions, derived therefrom, as to their significance for the practice of the invention.

Of course, the mechanism of calculation will not be indicated, for it is known to anyone acquainted with the ordinary mathematical analysis applied to the systems of differential equations. This mechanism or sequence may be easily reconstituted by the application of the current methods and will not be mentioned in the following explanation.

Under these conditions, I give the following 10 summary of the outlines of this fundamental theory:

Referring to Figs. 4, 5 and 6, let us examine a helicopter of the weight P (or mg), lifted by means of a propeller which furnishes a stress F 15 which is equal to P . Consequently, the machine keeps the air in a fixed point, neither rising nor sinking and without any side slip, if F is vertical.

The helicopter is given an initial inclination so that the force F , which is supposed to act always 20 in a constant direction relative to the machine, forms a very small angle α with the vertical line OY .

The result is a horizontal traction component 25 equal to $F \sin \alpha$ or $mg \sin \alpha$ or simpler $mg \alpha$; the angle and the sine may be interverted.

This horizontal component causes the machine to slide and it is supposed that this slip takes place in horizontal plane so that the centre of gravity of the machine originally situated at O 30 (origin of abscissas), moves always along the line OX without rising or sinking beyond this line.

I designs the moment of inertia of the machine, and it will be endeavoured to find out in different 35 cases the law of the variation of the angle α in dependency upon the time. In order to have a stable equilibrium, the angle α must have the tendency to become zero, when the time t increases indefinitely. Otherwise, the equilibrium 40 is unstable and the machine has the tendency to deviate more and more from its position of equilibrium.

Fig. 4 illustrates the case of the pure helicopter, i. e. a machine which is limited to a frame provided with an engine which drives a sustaining 45 system capable of balancing the weight P .

It is known that when a sustaining system is submitted to a substantially perpendicular displacement relative to the direction of the ascension force, there takes place a displacement of the centre of pressure, i. e. of the ascension force itself relative to the machine. The ascension force moves in the direction followed by the translation and has therefore the tendency 50 to raise the machine again and to prevent this machine from further sinking in the direction of its original inclination.

This displacement δ , which gives rise to an upward moment of forces, is proportional to the 60 velocity

$$\frac{dx}{dt}$$

65 at which the helicopter progresses along the line OX . Thus will be obtained the following system of equations:

$$\left\{ \begin{array}{l} m \frac{d^2x}{dt^2} = mg\alpha - S \frac{dx}{dt} \\ I \frac{d^2\alpha}{dt^2} = -F \frac{dx}{dt} \end{array} \right. \quad (I)$$

$$70 \quad \left\{ \begin{array}{l} m \frac{d^2x}{dt^2} = mg\alpha - S \frac{dx}{dt} \\ I \frac{d^2\alpha}{dt^2} = -F \frac{dx}{dt} \end{array} \right. \quad (II)$$

wherein S is a constant relative to the trail of the machine during its displacement along the line OX ; with slight velocities of displacement,

the trail is substantially proportional to the velocity, its form being:

$$\text{Trail equal to } k \cdot \frac{dx}{dt}$$

wherein k is a constant. In the Formula (II), F is a constant relative to the displacement of the centre of pressure. Eliminating

$$\frac{dx}{dt}$$

10

between these two equations, we obtain the resulting equation:

$$\frac{mI}{F} \frac{d^2\alpha}{dt^2} + \frac{SI}{F} \frac{d^2\alpha}{dt^2} + mg\alpha = 0 \quad (III)$$

15

the general integral thereof having the form:

$$\alpha = A e^{X_1 t} + B e^{X_2 t} + C e^{X_3 t} \quad (IV)$$

20

wherein X_1, X_2, X_3 are the roots of the characteristic Equation (V):

$$\frac{mI}{F} X^2 + \frac{SI}{F} X^2 + mg = 0 \quad (V)$$

25

The analytic examination of the problem shows that there is only one real root X_1 in the Equation (IV) and two conjugated imaginary roots. The real root is negative. As to the conjugated imaginary roots, these may be put down under the form:

$$X_2 = \lambda + \mu i$$

30

$$X_3 = \lambda - \mu i$$

The expression α may then be set under the form

$$\alpha = A e^{X_1 t} + e^{\lambda t} (B \cos \mu t + C \sin \mu t) \quad (VI)$$

35

By forming the sequence or curve of forces of Rolle and substituting in the form (V) in the ordinary manner, one can demonstrate with the aid of the ordinary mathematical methods that λ is always positive. α increases therefore indefinitely with the time, and there is no equilibrium possible.

Another case is shown in Fig. 5. It is supposed that the displacement in the forward direction of the centre of pressure of the propellers may be neglected on account of the use of very rapidly rotating propellers, which are therefore scarcely sensitive to the lateral displacements. On the other hand, the machine is surmounted by a plane Σ and has the tendency to be brought out of bank owing to the reaction R , which the displacement produces on the plane Σ . ρ is the distance of the application point of this resistance R to the centre of gravity O .

55

The fundamental equations are therefore

$$\left\{ \begin{array}{l} m \frac{d^2x}{dt^2} = mg\alpha - S \frac{dx}{dt} - S' \left(\frac{dx}{dt} + \rho \frac{d\alpha}{dt} \right) \\ I \frac{d^2\alpha}{dt^2} = -S' \rho \left(\frac{dx}{dt} + \rho \frac{d\alpha}{dt} \right) \end{array} \right. \quad (I')$$

60

$$\left\{ \begin{array}{l} m \frac{d^2x}{dt^2} = mg\alpha - S \frac{dx}{dt} - S' \left(\frac{dx}{dt} + \rho \frac{d\alpha}{dt} \right) \\ I \frac{d^2\alpha}{dt^2} = -S' \rho \left(\frac{dx}{dt} + \rho \frac{d\alpha}{dt} \right) \end{array} \right. \quad (II')$$

65

wherein S is the constant of the trail of the helicopter itself and S' is the constant of trail of the plane Σ .

70

The elimination of

$$\frac{dx}{dt}$$

75

between these two equations leads to the fundamental Equation (III')

$$\frac{mI}{S' \rho} \frac{d^2\alpha}{dt^2} + \left[\frac{(S+S')I}{S' \rho} + \rho m \right] \frac{d^2x}{dt^2} + \rho S \frac{dx}{dt} + mg\alpha = 0 \quad (III'')$$

80

under the condition that S be very small, which

75

is the case whenever use is made of small propellers rotating at a very high speed. It will be found further, that the general integral of the form

$$5 \quad \alpha = Ae^{x_1 t} + e^{\lambda t}(B \cos \mu t + C \sin \mu t) \quad (IV')$$

10 presents always positive values for λ . For this reason, the equilibrium is rendered as impossible as in the preceding case and the adjunction of an aerodynamic resistance above the general 15 centre of gravity has no other effect than that to cause resonant oscillations of the machine and to hasten its fall instead of stabilizing it.

15 In a third case, illustrated in Fig. 6, the machine is surmounted by a chamber 8 with any suitable gas filling, such as air or a light gas.

20 A designates the static pressure exerting its action on the envelope, the volume of this envelope being very important relative to the other elements of the helicopter.

The trail of the air screws may be neglected in comparison with that of the envelope. When the propellers furnish T, we obtain

$$25 \quad T + A = mg$$

25 The motor component of the yaw is:

$$T\alpha$$

30 The resistance of the whole to displacement, parallel to OX and of the velocity V, is:

$$S \times V,$$

S being a constant.

35 According to the indications of the Fig. 6, the system of equations is:

$$\begin{cases} m \frac{dx}{dt^2} = T\alpha - S \left(\frac{dx}{dt} + \rho \frac{d\alpha}{dt} \right) \\ I \frac{d^2\alpha}{dt^2} = -A\lambda\alpha - S\rho \left(\frac{dx}{dt} + \rho \frac{d\alpha}{dt} \right) \end{cases} \quad (I'') \quad (II'')$$

40 In these equations, ρ is the distance of the centre 0 from the centre of air resistance for a general displacement in the direction OX and λ is the distance of the centre 0 from the centre 45 of static pressure.

It is demonstrated, that in the expression of the general integral:

$$a = Pe^{x_1 t} + e^{\lambda t}(Q \cos \mu t + R \sin \mu t)$$

50 is negative under the condition that:

$$T - \frac{\rho m A \lambda}{I} < 0$$

which may be written (paying attention that $T + A = mg$):

$$T < mg - \frac{1}{1 + \frac{I}{\lambda \rho m}}$$

55 Thus, we have simply: $I = mr^2$.
The inequality is then:

$$T < mg - \frac{1}{1 + \frac{r^2}{\lambda \rho}}$$

60 If ρ be zero, that is to say if the machine is aerodynamically centered, the maximum value of T is:

$$T = mg$$

70 (the whole ascension realized by means of the air screws without any static ascensional effect), i. e. the equilibrium is always realized, since it is in the limit case.

75 It will be seen that when the machine is stabilized by the propeller thrust and centered, the

equilibrium is always stable and that it is only so under this sole condition.

Starting from these outlines, it is possible to put the invention into practice in different manners, various stages thereof being shown diagrammatically in Figs. 7 to 12, where for the sake of greater simplicity, the sustaining means have been omitted.

Use may be made for example of a fuselage, which is not a revolution body, such as illustrated in Figs. 7 and 8.

10 It is evident that such a fuselage may have a volumetric centre C different from the centre of air resistance R, as the said fuselage moves horizontally in a perpendicular direction relative to its greatest dimension, that is to say laterally along the line yy'.

15 A fuselage of this type may be provided by way of adjunction of a revolution shaped envelope with a keel Q (Figs. 9 and 10).

20 The conditions to be realized in this case require that the general centre of gravity of the whole machine (including always the air mass contained in the fuselage) be as near as possible to the point R, which is not to be confounded with the point C, for the condition of stabilization of the static couple requires in the contrary to part the point C as far as possible from R and place it above the latter.

25 It is to be noted that the arrangement as shown in Figs. 7, 8, 9 and 10, does not entirely realize the aims of the principle according to the invention. These are only realized as to the transversal displacement, the longitudinal displacement in the direction xx' must still be considered. (The air resistance to a displacement along Cy or Cy' is indicated by the arrows.)

30 It will be seen that as the fuselage moves in the direction xx', the centre of volume and the centre of air resistance are both situated on the line xx' itself. The air resistance is therefore placed too high with respect to the general centre of gravity and the conditions called for are not fulfilled. It is therefore necessary to lower the application point of the aerodynamic resistance in order to 45 obtain a displacement in the direction xx'.

35 For this purpose, all the elements offering resistance relative to the direction xx' may be placed as low as possible in points, such as r_1, r_2 (Figs. 11 and 12).

40 This arrangement does not substantially modify the location of the resistance to the transversal displacements, viz in the direction yy', and it results in the lowering of the centre of air resistance for the displacements in the direction xx'.

45 This arrangement, however, is far from being the most favorable one. Indeed, it is not possible to increase systematically the resistance to the displacement in the direction xx' with the single aim to attain a good centering. There is no means but to place the unavoidable air resistances of the machine at the most convenient and lowest possible points and to try, in the contrary, to diminish the said resistances to a minimum.

50 Moreover, it is not to be forgotten that these resistant elements (engine fuselage, passengers' nacelle) have each their volume which are to be added to that of the fuselage in order to determine the exact position of the centre of general volume.

55 By placing these elements as low as possible, we are sure to lower the centre of resistance, but simultaneously the centre of gravity and the

centre of volume are also lowered, although about a lesser distance, so that one cannot expect too much from this particular arrangement.

Fortunately, the centering of the machine, that 5 is the coincidence between the application point of the air resistance and the centre of gravity of this machine, does not need to be perfect any more when the velocity of the machine proceeding in the direction xx' increases.

10 Indeed, it must be remembered that the theory applies to a flying machine, which keeps the air in a fixed point, i. e. to velocities of horizontal displacement which may be neglected completely or almost completely and which do not exceed 15 in any case the few yards per second which represent the velocity of a yaw.

Consequently, the centering of the direction xx' is required only in the case where the machine keeps the air in a fixed point or at least has a 20 horizontal velocity of too slight a value to permit the tail fins of the machine to stabilize this machine in a sufficient manner.

25 For this purpose, there may be imagined a "provisional" centering system, which would produce the lowering of the aerodynamic resistance only in the case of slight velocities of translation in the direction xx' .

When the velocity becomes sufficient to insure 30 the stabilization of the machine by means of the said tail fins, it should be possible to retract this system so as not to impair the progress of the machine.

If all the above requirements are taken into 35 consideration, structures adapted for use in practicing my invention will result.

40 Figs. 13 and 14 illustrate one embodiment of the invention. In Figs. 13 and 14, C is the volumetric centre of the envelope or more exactly of the whole machine. Q is a keel, G the general centre of gravity, P_1 and P_2 are panels which may pivot about respective axes a_1b_1 and a_2b_2 so as to occupy for example the position, shown in dotted lines in Fig. 13. These panels do not substantially modify the application point of resistance to the displacement in the direction yy' , whatever may be their position on their axes a_1b_1 and a_2b_2 , owing to the presence of the keel. They modify however considerably the place of the application point of the air resistance for displacements in the parallel direction of xx' , when disposed perpendicularly to this axis xx' .

45 Care may be taken that the panels in combination with the fuselage of the centre C may insure a position of the air resistance to the displacement along xx' as near to the point G as possible. Under these conditions, the machine will be centered in all horizontal directions with a position of the volumetric centre higher than the centre of gravity.

50 The panels, such as P_1 and P_2 , may be replaced by propellers with variable incidence of the blades, such as h_1 and h_2 (Fig. 15).

55 When the machine moves in the direction xx' so that the propellers h_1 and h_2 have their blades at zero incidence, there will be an immediate increase of the resistance on the part of these propellers which attack the air with an incidence which is different from the zero position. These propellers fulfil then the task of the panels P_1 and P_2 in their transversal position.

60 When on the contrary, it is desired to pass to a higher translational velocity, the pitch of these propellers may be modified in such a manner that these cease to offer any resistance to the air, allowing for a displacement of the machine along xx' .

They may even be placed so as to become propulsive; thus, their brake effect ceases to have any influence and may even form a traction force.

65 It will be observed that the propellers h_1 and h_2 , which must be controlled by the pilot, permit of doing so with great efficiency during a yaw in the direction xx' , the machine keeping then the air in a fixed point.

70 When the machine is driven for example in the direction Cx and when the propellers h_1 and h_2 , too small for example to effectively oppose the horizontal displacement along Cx , cannot insure the centering by sufficiently lowering the general point of resistance, the pilot may increase their effect of resistance by conveniently operating 15 the steering part, thus determining even with small propellers the desired centering, each time with the aid of the steering set.

75 Besides, it is possible to conceive automatic devices which produce the desired result. In general, it is preferable that the system in itself be capable to insure the centering without any attention of the pilot.

80 In order to attain the desired effect, the propellers h_1 and h_2 must be of considerable size and 25 must be provided with a sufficient number of blades, for otherwise their resistance would be in general slightly inferior to that of a plane with a surface which is equal to the circle which they describe.

85 It is to be noted that these propellers are arranged in the normal manner to obtain the desired result, when use is made of the system with inclined propellers. Indeed, it is necessary to complete the action of the principal propellers, such as H (Fig. 16) by providing auxiliary propellers, such as h , unfolding components of traction t capable of resisting to the components of traction t' of the principal propellers H , and it will be seen that a system of this type, moving 40 in the direction xx' , meets with an increasing resistance along the line x_1x_1' , so that the translational displacement takes place in the direction Cx or in the direction Cx' .

90 The plane of the propellers h extends in the direction Cx_1 , the thrust of the propellers H having a component extending in the direction Cx' .

95 When the machine moves in the direction Cx , the horizontal component of traction of the principal propellers diminishes while the counter effort t of the propellers h increases. There appears thus a resistance to the displacement in the direction x_1x_1' having the same effect as the panels P_1 and P_2 , as mentioned above.

100 When on the contrary this displacement takes place in the direction Cx' , the thrust of the propellers h diminishes, since these propellers move in the direction of their effort of traction, without their velocity of rotation being changed. There appears again a resistance in the direction x_1x_1' which is opposed to that in which the translation tends to exert its influence.

105 In summary, with the arrangements according to Fig. 16, if the dimensions of H and h are judiciously chosen, that is, calculated in such a manner that the general resistance of the craft to any displacement in the direction xx' comes as close as possible to the centre of gravity G, it will be then sufficient to provide the fuselage with a keel Q, which insures the aerodynamic centering 70 in a perpendicular direction to xx' .

110 Fig. 17 shows an end view of a machine such as described with reference to Fig. 16, comprising the keel, the auxiliary propellers and the panels as well as the inclined propellers.

Various changes may be made in the details disclosed in the foregoing specification without departing from the invention or sacrificing the advantages thereof.

5 I claim:

1. In an aircraft of the helicopter type, an air-filled cell having its volumetric center midway its depth at the center of its longitudinal axis, the center of gravity of the aircraft being spaced downwardly from the said volumetric center, and a lifting screw device located downwardly from the center of gravity whereby for each horizontal displacement the resistance opposed to such displacement by the ambient air is applied at a point situated close to the center of gravity and below the center of volume of the aircraft.
- 10 2. In an aircraft of the helicopter type, an air-filled cell elongated horizontally and having a depending longitudinally extending keel, the volumetric center of the aircraft being midway

the length of the longitudinal axis of the cell and the center of gravity being between the volumetric center and the bottom of the cell, and propellers mounted at opposite sides of the keel and each angularly adjustable about a horizontal axis.

3. The structure of claim 2 wherein a pair of the propellers are located adjacent the front end of the keel with the keel between the same and the second pair of propellers are located intermediate the length of the keel rearwardly of the longitudinal center of the keel whereby the front propellers may be set to direct air blasts rearwardly at an upward incline and the rear propellers set to create air blasts intersecting air blasts of the front propellers.

4. The structure of claim 2 wherein the propellers are provided with adjustable blades for increasing the resistance to horizontal displacement in the axial direction of the air-filled cell.
